UNITED STATES PATENT OFFICE.

MERRILL O. STEERE, OF PAWTUCKET, RHODE ISLAND.

LOOM STOP-MOTION.

SPECIFICATION forming part of Letters Patent No. 774,285, dated November 8, 1904.

Application filed November 12, 1902. Serial No. 131,057. (No model.)

To all whom it may concern:

Be it known that I, MERRILL O. STEERE, a citizen of the United States, residing at Pawtucket, in the county of Providence and State 5 of Rhode Island, have invented certain new and useful Improvements in Loom Stop-Motions, of which the following is a specification.

My invention relates particularly to narrow-ware looms; and the object is to provide 10 improved means for stopping the loom upon accidental misplacement or wrongly-timed movement of the shuttles or of the shuttle-actuating mechanism.

My improvement consists chiefly in so 15 constructing the device that it shall be positive and quick of action and in so adapting it to the loom that it shall not occupy so much space as to curtail the shuttle-carrying capacity of the latter.

20 The following is a complete description of the invention and its mode of operation, illustrated by the accompanying drawings, in which—

25 Figure 1 is a front view of a portion of a loom, showing my device attached; Fig. 2, a view looking toward the end of the loom, part sectional, on the line A A, Fig. 1; Fig. 3, a modification.

30 My invention consists, briefly, in mechanism 35 to be acted upon by the shuttle rack-bar or other shuttle-actuating device whenever the latter is misplaced or its movement wrongly timed in relation to the movement of the lay to stop the loom.

35 Referring to the drawings, *a* represents one of the loom end frames, *b* the breast-beam extending therefrom, and *c* the reciprocating lay or batten.

40 The stop-motion device is adapted to be supported adjacent the end frame of the loom, preferably at that end of the loom on which the driving mechanism is located. As 45 shown in Fig. 2, I provide an angular bracket *d*, adapted to be secured to the breast-beam *b* and having projecting lugs to form bearings for the operating mechanism of the stop-motion. Sliding in slots in the two upward-extending lugs *e* and *f* is a horizontal rod or bar *g*, adapted to be moved by the shuttle 50 rack-bar to release the stopping devices of

the loom. One end of the rod *g* is beveled on the under side and engages a similarly-beveled end of the vertical rod *j*. The rod *g* is held in normal position by the spring *h*, which, acting between the lug *e* and the collar *i*, secured to the rod *g*, presses it toward the rack-bar *c*, the said collar also acting to limit the movement of the rod *g* under the action of the spring. The rod *j* is adapted to slide in the bearings *k* and *l* at the front of the frame 60 *d* and is formed with a detent *m* at its lower extremity to engage the shifter-bar *n*. A helical spring *j'*, supported on the bearing *l* and acting on the collar *j*, forces the rod upward, maintaining the detent *m* in position 65 for engagement with the shifter-bar *n*. The detent *m* is preferably formed, as shown in Fig. 2, by bending the end of the rod *j* at a right angle to its body portion and is adapted to engage a catch *o* in the under side of 70 the shifter-bar *n*. The latter is operatively connected with the power-controlling mechanism and by its longitudinal movement acts to stop the loom. As illustrated in the drawings, a belt-shipper *p* of usual structure is 75 provided to shift the driving-belt *q* from the loose to the tight pulley to start the loom and vice versa to stop it. The shipper *p* is moved through the lever *r*, suitably connected therewith and operated manually through a hand-rod *s*, connected to the upper end of the lever *r* and running the length of the loom parallel to the breast-beam. The shifter-bar *n* engages the lever *r* to shift the belt *q* when automatic stopping is required. Sliding in the 85 brackets *t* and *u*, the bar is pressed outward to engage the lever *r* by a helical spring *v*, bearing on the bracket *u* and acting on a collar *w* on the bar. A forked end *y* (not shown in Fig. 2) is provided on the lever *n* to straddle the lever *r*, insuring a positive engagement between the two. It will be noted that the lever *r* is movable independently of the shifter-bar to stop the loom by hand without releasing said bar. The bars *g*, *j*, and *n* are 95 held in their respective bearings by the pins *z*, *z*, &c., which take the side thrust of the bars.

To release the detent-rod and allow the shifter-bar to act, I have devised the follow- 100

- ing novel means: The rack-bar c' is adapted to engage the end of the release-rod g if accident misplaces it or wrongly times its movement in relation to the movement of the lay.
- 5 Normally during part of the movement of the lay the bar g passes through one or the other of two openings c^2 c^3 , extending through the rack-bar. As well known to those versed in the art, the longitudinal reciprocation of the 10 rack-bar takes place with the lay at or near its farthest backward position, and I adapt the length of the rod g to provide for the rack-bar clearing its end during said movement.
- The operation of the device is as follows:
- 15 To start the loom, the belt is shifted from the loose to the tight pulley through the lever r by means of the hand-rod s . The movement of the lever r slides the shifter-bar n , compressing its spring v until the catch in its under side registers with the detent on the rod j . The latter is forced upward by the spring j' and engages the catch in the shifter-bar to retain the latter in the position indicated in Fig. 1. The rack-bar c' traverses back and 20 forth to throw the shuttles, passing transversely of the rod g beyond its extremity. At the completion of each stroke one or the other of the openings c^3 is opposite the end of the bar g , and the latter is protruded through 25 the opening during the finish of the forward stroke of the lay. If now any accident befalls a shuttle, such as jamming in its blocks or being otherwise held from reciprocation at the proper time, the rack-bar, through its connection with the shuttles, is affected and fails 30 to move. It will be evident that if the rack-bar fails to accomplish the extent of its longitudinal movement while beyond the end of the bar g the latter will not register with and 35 pass through its opening in said rack-bar. Hence upon the forward movement of the lay the solid portion of the rack-bar will engage the rod g and pressing it outward force down the detent-rod j through the engagement of 40 the beveled sections, thereby releasing the shifter-bar n . Through the tension of the spring v the latter will be forced outward to throw the lever r , and thereby shift the belt to stop the loom.
- 45 In most devices for the purpose herein described it has been the practice to employ a "dummy" shuttle, so called, for acting upon the stopping mechanism. This arrangement consisted of the body portion of the shuttle 50 traveling in the blocks at one end of the lay and adapted on wrongly-timed movement to engage the releasing mechanism. It will be evident, however, that such an arrangement 55 curtails the product of the loom, since the dummy displaces one operative shuttle. In 60 my device the full complement of shuttles may be used in the loom.

Means have been before devised to perform the automatic stopping so disposed and arranged as not to require the dummy shuttle,

but which, nevertheless, by its bulk and because of the movement of projecting members consumed space which might otherwise be available for weaving. In my device the mechanism is so compacted and so disposed 70 as to require a minimum amount of space and to be out of the way of the operator, while accessible for oiling or repair.

While I have described my device in combination with the rack-bar of a loom, it is 75 evident that the mechanism might be operated by any other appropriately-going member and also that modifications might be made in the form and arrangement of its parts without departing from the scope of this invention. For example, Fig. 3 shows a form of the device in which the vertical rod j bears upon the top of the shifter-bar n , thereby requiring no hook to be formed at its lower extremity to constitute the detent. In such 80 case the vertical rod j is formed with an opening near the top in line with the horizontal rod g . The top edge of the opening is rounded to correspond with the bevel at the end of rod g , so that when the latter is 85 shifted to press against the rod j rod j is raised, disengaging its lower extremity from the detent-rod n .

Therefore, without limiting myself to the precise construction and arrangement shown 90 and described, I claim as my invention—

1. The combination with the lay, shuttles and shuttle-actuating rack-bar of a loom, of a stop-motion comprising a sliding shifter-bar actuated to govern the power-controlling 100 mechanism, a detent to maintain the shifter-bar inoperative, and a release-rod so related to the rack-bar as to be normally protruded through openings in the latter on the forward movement of the lay, but engaged thereby 105 on a wrongly-timed movement to release the detent to stop the loom.

2. The combination in a stop-motion for looms, of a spring-pressed shifter-bar, a detent-rod adapted to engage a catch in the 110 shifter-bar and having a beveled extremity, and a release-rod formed with a beveled end to engage that of the detent-rod and adapted to be moved by a going member of the loom to release the detent-rod substantially as shown 115 and described.

3. The combination in a stop-motion for looms, of a sliding shifter-bar, adapted to operate the power-controlling mechanism, means to slide the bar, a detent-rod adapted 120 to engage the shifter-bar to maintain it inoperative, and a release member engaging the detent-rod and so related to a going member of the loom as to normally clear the latter but engaged thereby on an ill-timed movement to stop the loom.

4. The combination in a stop-motion for looms with the breast-beam, lay, shuttles and rack-bar, of a bracket adapted to be fastened to the breast-beam and having projecting 130

lugs with bearings, a horizontal rod adapted to slide in said bearings, and having a beveled extremity, a collar on the rod, a spring acting between said collar and one of the bearings of the bracket to maintain the rod in position to be protruded through openings in the rack-bar on the forward movement of the lay, a vertical detent-rod sliding in bearings at the front of the bracket formed with a beveled upper extremity to engage that of the horizontal rod and having a bent lower extremity, a collar on said rod, a spring acting between the collar and one of the bearings of the bracket to press the rod upward, a horizontal shifter-rod sliding in bearings at the front of the loom to govern the power-controlling mechanism and having a catch to be engaged by the bent portion of the detent-rod, a collar on said rod and a spring acting between the collar and one of the bearings to slide the rod, all substantially as and for the purpose described.

5. The combination, in a stop-motion for looms, of the lay, shuttles, and perforated shuttle-actuating bar, of a sliding shifter-bar 25 operatively connected to the power-controlling mechanism, a detent to maintain the shifter-bar inoperative, and a rod in the line of movement of the shuttle-actuating bar, operating through the detent on the shifter- 30 bar to control the stopping.

6. The combination of the lay, shuttles, and perforated shuttle-actuating bar, of a bevel-ended rod in the line of movement of the shuttle-actuating bar, a bevel-ended rod 35 suitably supported at an angle to the first rod, and a shifter-bar controlled by the latter.

In testimony whereof I affix my signature in presence of two witnesses.

MERRILL O. STEERE.
